CLAIM

The ornamental design for a fume hood monitor, as shown and described.

DESCRIPTION

FIG. 1 is a perspective view of a fume hood monitor in accordance with the present invention;

FIG. 2 is a front side view of the fume hood monitor of FIG. 1;

FIG. 3 is a left side view of the fume hood monitor of FIG. 1;

FIG. 4 is a right side view of the fume hood monitor of FIG. 1;

FIG. 5 is a top side view of the fume hood monitor of FIG. 1; and,

FIG. 6 is a bottom side view of the fume hood monitor of FIG. 1.

The portions illustrated in broken lines on the figures are for illustrative purposes only and form no part of the claimed design.

The broken lines depict unclaimed environmental subject matter.

1 Claim, 6 Drawing Sheets
